THEOPHILUS A. AUBERLIN, OF DETROIT, MICHIGAN.

Letters Patent No. 95,181, dated September 28, 1869.

IMPROVEMENT IN PERMUTATION-LOCKS.

The Schedule referred to in these Letters Patent and making part of the same

To whom it may concern:

Be it known that I, THEOPHILUS A. AUBERLIN, of Detroit, in the county of Wayne, and State of Michigan, have invented a new and useful Improvement in Combination-Locks; and I do declare that the following is a true and accurate description thereof, reference being had to the accompanying drawings, and to the letters of reference marked thereon, and being a part of this specification, in which—

Figure 1, sheet 1, is an elevation of the interior of the lock, with the cover removed.

Figure 2 is a horizontal section through the case on the line *w w* in fig. 1, showing a plan of the mechanism.

Figure 3 is a side elevation of the combination-wheels and tumbler-plate, with a vertical section of the bolt.

Figure 4 is a cross-section of the spindle and cylinder, showing the washer.

Figure 5 is a vertical section of the cylinder, tumbler-plate, and cap.

Figure 6 is an elevation of the knob and dial-plate.

Figure 7, sheet 2, is a vertical section of the lock and case, through the line *x x* in fig. 2, with the tumblers removed, showing a plan of the oscillating-bolt and changing slide.

Figure 8 is the same, on the line *y y* in fig. 2, with the slide drawn back, and the tumblers out of gear therewith, ready for changing the combination.

Figure 9 is a front elevation of the dog or lever.

Figure 10 is a bottom plan of the same.

Figure 11 is a horizontal section of a tumbler and tumbler-carrier on the line *z z* in

Figure 12, which is a plan of the same.

Similar letters of reference indicate like parts in each figure.

The nature of this invention relates to an improved construction of combination-locks, and consists, primarily, in the peculiar arrangement of the dog and tumblers on the bolt, which oscillates on a tube projecting inwardly from the front plate of the lock, and operated by the spindle, through a series of peculiar tumblers; and,

Secondly, in a novel method of changing the combination, and in the general arrangement of its parts, as hereinafter more fully shown and set forth.

In the accompanying drawings—

A represents the lock-case, cast with a central inward-projecting cylinder, *B*, also with a stump, *a*, on the inner side of the front-plate.

C is a bolt, of the form shown in fig. 7, sleeved on the cylinder *B*, on which it oscillates, its front end being arrested in its upward passage, when thrown by a stop, *b*, in the front plate of the case, and in its downward movement by a similar stop, *b'*.

The bolt has attached to its inner end an inward-

projecting angular stump, *c*, and on its upper part a stud, *c'*, on which is sleeved the dog *D*, shown in figs. 9 and 10.

E is the changing slide, cruciform in shape, with an opening in its centre, through which passes the cylinder *B*, and a slot in each of its horizontal arms, through the inner one of which projects the stump *c*, and through the outer a screw, by means of which it is secured to the bolt *C*, in such a manner that it may slide laterally thereon.

Under the inner arm of the slide, the bolt *C* is provided with a tumbler, *d*, by means of which, and the key-stump *d'* on the bolt, the slide may be moved laterally, by a proper key, inserted from the back of the lock, turning on said stump, which movement becomes necessary when the combination is to be changed.

The slide *E* is also provided with a hollow internally-threaded stud, *e*, on each vertical arm, on which are secured, by proper screws entering these studs, the tumbler-carriers *F*, fig. 12, on each of which is an annular tumbler, *F'*.

A series of small clamps, *f*, projecting up from the circular opening in the carrier, embraces the bevelled internal edge of the tumbler, and holds it in place against the carrier, but allows it to rotate freely thereon. Each tumbler has cut in its periphery a slot, *g*, into which the stub, *h*, of the dog *D* drops, when all the tumblers are in position to throw the bolt.

An angular recess or notch, *i*, is also formed in the edge of each tumbler, at the same place in each, with relation to the slot *g*. When the slide is moved back, carrying with it the tumblers, these recesses embrace the angular stump *c*, on the bolt, holding the tumblers stationary, disengaged from the combination-wheels, while the combination is being changed. Each tumbler is also provided with an angular stud, *j*, for the purpose hereinafter shown.

G are toothed combination-wheels, usually three in number, revolving on the cylinder *B*. They are provided with as many teeth as there are numbers on the dial; also, with a stud, *k*, projecting through from each side, except that next the front plate of the lock, whose stud projects inwardly only.

When the lock is set upon a combination, the stud *j* of the tumbler is in engagement with the space between two of the teeth on the combination-wheel, but when it is desired to change the combination, the stud is out of gear with the combination-wheel, as shown in fig. 8, allowing the wheel to be revolved, without moving the tumblers. These studs are so placed in the wheels, that in revolving them, the stud on each successively strikes the stud on the next wheel; and moves that wheel around with it.

It will be noticed that the cylinder *B* is provided with an external slot or groove, *l*, fig. 4.

Between the first and second, and second and third

combination-wheels, a ring, *m*, is placed on the cylinder, to serve as a washer, preventing one wheel from communicating motion to the next, except through the studs *k*, in the manner described. To prevent the washer from turning, it is cut, and the ends turned into the slot *l*, as shown. A divided ring of wire, *n*, fig. 3, fitting into a groove around the inner end of the cylinder, retains the first wheel in place.

o are washers on the studs *e* of the slide *F*, between the tumbler-carriers, to keep the latter in their relative positions, which are there retained by screws entering the hollow studs. The tumblers and wheels being in place, the dog *D* is slipped over its stud *c'*, and secured by a screw entering said stud.

H is a dial-plate, on the outside of a door, *I*, and is provided with the usual index or mark, *p*, from which the combinations are worked.

J is a handle or knob, provided with a graduated dial, *q*, to the centre of which is secured the spindle *K*, which projects through the cylinder to the interior of the lock. The inner end of the spindle is threaded, and has its extremity flattened on one side, as shown in fig. 1.

L is a tumbler-plate, provided with a threaded hub, by means of which it is screwed on the end of the spindle. It is also provided on its under side with a stud, *r*, fig. 3, which, when the plate is revolved, comes in contact with the stud *k* of the tumbler under it, and rotates the latter. It is further provided with a slot in its periphery, into which the stub of the dog *D* drops, when the slots in the tumblers are in line with said slot, as shown in fig. 1.

The parts being in place, to operate the lock and throw the bolt, turn the knob to the left until the slots *g* of the tumblers are under the stub of the dog *D*, then, by turning to the right one revolution, the slot in the tumbler-plate *L* will come under the stub, which will then drop into all the slots; by turning a little further, the bolt will be thrown up, the end of the stub passing under the stump *a*, is prevented from rising out of the slots, while the bolt is being revolved. Reversing the movement, the end of the bolt will strike

the stop *b'*; continuing, the under face of the stub being bevelled, it will be lifted out of the slot by their square shoulders, when two or three revolutions of the knob are made, the combination-wheels will be successively disarranged.

To change the combination, say from fifty (50) to any desired one of three numbers, revolve the knob four times to the left, and stop with 50 directly under the mark on the dial-plate, insert the key through the hole in the back-plate, and turn it to the left three-quarters of a revolution, which movement will draw back the slide and throw the tumblers out of gear. The lock is now ready to set.

Revolve the dial four (4) times to the left, with the first selected figure at the mark, then turn to the right three (3) times to your second figure, stopping under the mark; then turn to the left two (2) revolutions, stopping with your third figure under the mark; turn the key to the right and withdraw it; then move the dial slowly to the right until its blank space passes under the mark, when it will answer the new combination, and the bolt be thrown.

To lock it, revolve the knob to the left once or twice. To open or unlock, observe the same rule as in setting the combination, except that of inserting the key.

What I claim as my invention, and desire to secure by Letters Patent, is—

1. The bolt *C*, provided with tumbler *d*, stump *e*, key-stump *d'*, and stud *c'*, on which is sleeved the dog *D*, arranged and operating in the manner and for the purposes set forth.
2. In combination with said bolt, the slide *E*, provided with studs *e*, substantially as and for the purpose specified.
3. The annular tumblers *F*, each provided with a slot, *g*, notch *i*, and stud *j*, the tumbler-carriers *F* and clamps *f*, arranged and operating in the manner and for the purpose set forth.

THEOPHILUS A. AUBERLIN.
